UNITED STATES PATENT OFFICE

156,859

FILING MACHINE OR THE LIKE

Daniel J. Williams, Fairfield, Conn., assignor to
Connecticut Tool & Engineering Company,
Bridgeport, Conn., a corporation of Connecticut

Application September 3, 1948, Serial No. 148,448

Term of patent 14 years

(Cl. D37—1)

To all whom it may concern:

Be it known that I, Daniel J. Williams, a citizen of the United States, residing at Fairfield, county of Fairfield, and State of Connecticut, have invented a new, original, and ornamental Design for a Filing Machine or the like, of which the following is a specification, reference being had to the accompanying drawings, forming part thereof.

Figure 1 is a front view of a filing machine or the like, showing my new design.

Fig. 2 is a side view thereof looking from the right of Fig. 1.

Fig. 3 is a side view thereof looking from the left of Fig. 1.

I claim:

The ornamental design for a filing machine or the like, as shown.

DANIEL J. WILLIAMS.
